US00D928478S

(12) **United States Design Patent** (10) **Patent No.:** **US D928,478 S**
Gerig (45) **Date of Patent:** ** *Aug. 24, 2021

(54) **SHOE**(71) Applicant: **NIKE, Inc.**, Beaverton, OR (US)(72) Inventor: **Kristina Gerig**, Portland, OR (US)(73) Assignee: **NIKE, Inc.**, Beaverton, OR (US)

(*) Notice: This patent is subject to a terminal disclaimer.

(**) Term: **15 Years**(21) Appl. No.: **29/705,627**(22) Filed: **Sep. 13, 2019****Related U.S. Application Data**

(63) Continuation of application No. 29/648,238, filed on May 18, 2018, now Pat. No. Des. 874,104.

(51) **LOC (13) Cl.** ..... **02-04**(52) **U.S. Cl.**USPC ..... **D2/947**(58) **Field of Classification Search**

CLAIM

The ornamental design for a shoe, as shown and described.

DESCRIPTION

FIG. 1 is a first side view of a shoe showing my design;

FIG. 2 is a second side view thereof;

FIG. 3 is a rear view thereof;

FIG. 4 is a first side perspective view thereof; and,

FIG. 5 is a second side rear perspective view thereof.

The even-length broken lines represent unclaimed subject matter and form no part of the claimed design.
